UNITED STATES PATENT OFFICE.

HENRY C. MARX, OF CHICAGO, ILLINOIS.

COMBINED METALLOPHONE AND ZITHER.

1,272,832.

Specification of Letters Patent.

Patented July 16, 1918.

Application filed July 2, 1917. Serial No. 178,161.

To all whom it may concern:

Be it known that I, HENRY C. MARX, a citizen of the United States, and a resident of Chicago, in the county of Cook and State 5 of Illinois, have invented certain new and useful Improvements in Combined Metallophones and Zithers, of which the following is a specification.

This invention relates to improvements in 10 a musical instrument of the metallophone zither type, and it consists in certain peculiarities of the construction, novel arrangement and operation of the various parts thereof as will be hereinafter more fully set 15 forth and specifically claimed.

One of the objects of the present invention is to provide a musical instrument wherein a series of metal bars tuned to a musical scale, like those of orchestra bells, 20 are combined and associated with a series of grouped musical strings capable of being tuned to musical chords to harmonize with the metal bar scale, whereby said metal bars, which will always remain in tune, will 25 act as a guide by which the chord strings can be tuned.

Other objects and advantages of the invention, will be disclosed in the following description and explanation.

30 In the accompanying drawing which serves to illustrate an embodiment of the invention,

Figure 1, is a plan view of the instrument showing a portion of the sounding box or 35 casing removed and some of the metal bars and the support therefor omitted or broken off.

Fig. 2, is an end elevation of a fragment of the sounding box, showing means for 40 holding the music sheet.

Fig. 3, is a longitudinal sectional view taken on line 3—3 of Fig. 1, looking in the direction indicated by the arrows showing the bottom of the sounding box shortened 45 for the convenience of illustration, and

Fig. 4, is a perspective view of a spring hammer used in playing the instrument.

Like numerals of reference, refer to corresponding parts throughout the different 50 views of the drawing.

The reference numeral 5 designates the sounding box, as a whole, which box is by preference, rectangular in shape as shown and has its bottom 6, by preference, located 55 within the same at a slight distance from the lower edge of the box as is clearly

shown in Fig. 3 of the drawing. One end of the bottom 6, which may be termed the front end thereof, is extended from the adjacent end of the box 5 to provide a key and finger board for the strings of the instrument. The top of the box 5 is partially closed by means of a pair of strips 7 and 8 which are located longitudinally with respect to the box and in parallelism with one another yet so as to afford an open space between their adjacent edges as will be readily understood by reference to Fig. 1 of the drawing. These strips or pieces 7 and 8 are secured to the edges of the sides and 70 ends of the box in any suitable manner. Located horizontally and transversely on the inner surface of each of the end pieces of the box 5 is a cleat 9 on which the ends of the rails 10 extended from one end of the box 75 to the other rest. These rails are spaced apart in parallelism with one another and they as well as the cleats 9 are located above the strings 11 of the instrument. These strings are secured at one of their ends by 80 means of hitch pins 12 to the upper surface of the bottom 6 of the sounding box near the rear end of said bottom, as shown in Fig. 1 of the drawing. Near that end of the bottom 6 on which the hitch pins 12 are mounted 85 said bottom is provided with a bridge 13 to support the strings and the extension 14 or key and finger board is provided near its front end with a bridge 15 to support the strings 11 near their front ends, which ends 90 are connected to suitable tuning keys 16 or pegs of the ordinary or any well-known construction. As shown, the strings 11 are arranged in groups, each group consisting of 95 four strings.

Located on the upper surface of each of the rails 10 is a strip 17 of felt or other suitable material which strips extend from one end of the rails to the other end thereof and may be secured thereto in any suitable 100 way. Mounted transversely on the strips 17 and rails 10 are a series of metal bars 18 each of which has near each of its ends an opening 19 through which openings are extended pins 20 which are seated in the rails 10 and are somewhat smaller than the openings 19. The upper portions of the pins 20 are connected together by means of cords or wires 21 employed for the purpose of preventing dislocation of the bars 18. The 110 metal bars 18 are arranged in octaves and in the present instance I have shown the instru-

ment provided with two octaves only, although a portion of one of said octaves is omitted from Fig. 1 of the drawing. These bars are tuned to a musical scale and the 5 strings 11 are tuned to musical chords to harmonize with the scale of the bars.

In order to produce sounds on the metal bars 18 any ordinary mallet or suitable hammer may be employed but to obtain the best 10 results, or in order to produce soft tones or louder tones I prefer to use a hammer of the construction shown in Fig. 4 of the drawing which consists of a handle 22 which has at one of its ends a resilient shank 23 on the 15 free end of which is mounted a hammer 24 one end of which is provided with a cushion 25 which is employed to produce soft or low tones or sounds when the bars 18 are struck thereby. The handle 22 of the hammer is 20 provided at one of its ends with a cushion 26 which is located directly under the inner end of the shank 23 and is intended to be used when it is desired that the hammer should repeatedly strike the metal bars to 25 produce tremolo. When this is done the cushion portion of the handle is brought in contact with one of the strips 7 and 8 of the sounding box, usually the strip 8, when it is obvious that the cushion 26 will prevent 30 any noise occasioned by the impact of the handle 22 with said strip which would occur if the cushion is not used.

The box may be provided in one of its sides with a kerf 27 which is disposed downwardly and inwardly from the outer surface 35 of the box and is for the purpose of holding a card 28 on which the music may be printed or which may support an ordinary sheet of music in the proper position to be easily 40 read by the player.

In order to enable those skilled in music to readily understand the invention and its operation, I have illustrated in Fig. 1 of the drawing a tuning chart 29 mounted or 45 displayed on the extension 14 on which I have shown four groups of chords; the one numbered 1, being tuned to give the tonic or first chord in the key of C; the one numbered 2, being tuned to a dominant seventh

or second change of said key; the one numbered 3, being tuned to a sub-dominant or a third change of the key; and the one numbered 4, being tuned to the tonic chord of D.

On the strip 7, or top of the sounding box, is shown a scale of notes to indicate the pitch 55 to which the metal strips are tuned. The numerals on said strip, are intended to be used in connection with music sheets specially prepared for use in connection with the instrument to indicate the metal strips 60 to be struck or played upon.

Having thus fully described my invention, what I claim as new and desire to secure by Letters Patent is—

1. In a musical instrument, the combination 65 with a sounding box, of a series of metal bars tuned to a musical scale and mounted within said box, and a series of grouped musical strings capable of being tuned to musical chords to harmonize with the metal 70 bar scale and also mounted within said box but below said strips.

2. In a musical instrument, the combination 75 with a sounding box, having a longitudinal opening in its top and an extension projected from the lower part of one of its ends, of a series of tuned metal bars mounted across and below said opening, a series of grouped musical strings mounted longitudinally within said box and over said extension, and means on said extension to tune the 80 strings.

3. In a musical instrument, the combination 85 with a sounding box having an extension projected therefrom, of a series of tuned metal bars mounted in the box, a series of musical strings mounted in the box and extended longitudinally over said extension, and means to tune the strings.

4. In a musical instrument, the combination 90 with a metallophone of musical strings tuned to furnish a plurality of chords and mounted under the bars of the metallophone.

HENRY C. MARX.
